UNITED STATES PATENT OFFICE.

ADDISON S. HODGES, OF CHELSEA, MASSACHUSETTS.

APPARATUS FOR MOLDING SASH-WEIGHTS, &c.

SPECIFICATION forming part of Letters Patent No. 411,441, dated September 24, 1889.

Application filed February 19, 1885. Renewed March 2, 1889. Serial No. 301,815. (No model.)

To all whom it may concern.

Be it known that I, ADDISON S. HODGES, a citizen of the United States, residing at Chelsea, in the county of Suffolk and State of Massachusetts, have invented certain new and useful Improvements in Molding Apparatus; and I do hereby declare that the same are fully described in the following specification, and illustrated in the accompanying drawings.

This invention relates to improvements in molding apparatus for sash-weights and similar articles, and it is carried out as follows: Patterns shaped similar to the body of the weight, but considerably longer to allow of different lengths of weights being made from the same patterns, are placed on a mold-board which is grooved, so as to allow the patterns to rest with one-half above and one-half below the upper surface of the mold-board. The mold-board is made nearly twice the length of the pattern, (if you wish to cast two rows of weights in the same flask,) so that two patterns may be placed in the same groove 25 with their tapering ends abutting against the edge of a gate-pattern, placed on the mold-board in suitable guides. The lower half of a two-part flask is then placed upside down on the mold-board in such a manner that the 30 weight and gate patterns project beyond the side and ends of the flask, the flask being grooved on its edges to allow it to rest on the mold-board. The flask is then rammed up with sand and leveled off. The bottom board 35 of the flask being placed on top of the flask and the whole turned right side up, I remove the mold-board, leaving the gate and weight patterns partly embedded in the sand. The upper or remaining half of the flask is then 40 placed in position on top of the lower half and a sprue and shutting-off pattern placed edgewise on the gate-pattern that is embedded in the sand, the sprue-pattern being placed in or near the center of the gate-pattern, and 45 the shutting-off pattern being placed against the side of the flask where the gate-pattern projects through the flask. A cutting-off pattern is also placed at each end of the flask over the weight-patterns at different distances 50 from the ends of the weight-patterns, according to the size of the weights that are to be

cast. Suitable marks are made on the weight-patterns to denote the position to place the cutting-off patterns. If necessary, one or more pieces may be placed between the cutting-off pattern and the end of the flask to fill the space left between the same and to prevent the sand from moving the cutting-off pattern when the remaining half of the flask is rammed up with sand. After the upper 55 half of the flask has been filled with sand and leveled off the top board or boards of the flask are placed on the flask and the whole clamped together by means of suitable clamps or by a weight being placed on top of the top 60 boards. The gate-pattern is now removed by drawing on the end of the same which projects through the perforation in the side of the flask and the sprue and shutting-off 65 patterns removed from the top of the flask. 70 The hole made in the sand by the removal of the latter is then partially filled and rammed with sand, and as the said hole communicates with the outer end of the gate made by the removal of the gate-pattern it will be seen 75 that the gate is shut off at this by the sand in said hole, thereby preventing the escape of metal from the mold at this point when the metal is poured into the mold. The hole made by the withdrawal of the sprue-patterns serves 80 as an opening through which the metal is poured into the mold, as usual. I now draw the weight-patterns from the sand through the perforations in the ends of the flask, and also the cutting-off patterns from the top of the 85 flask, leaving an easy access to the spaces made in the sand by the removal of the weight-patterns for the placing of the thimbles (more fully described hereinafter) in said spaces, and also to allow a sufficient amount of sand 90 to be put back of said thimbles after they have been placed in position to prevent the metal from forcing the thimbles back and from escaping.

The thimble which I place in the space 95 made by the weight-patterns is made of a cylindrical block of cast-iron, chambered out at one end to receive and hold the eye for the weight in such a position that the ends of the eye project beyond the end of the thimble 100 into the space in the sand made by the weight-pattern when said thimble is placed in posi-

tion, so as to allow the metal to surround the ends of the eye and embed the same in the weight. The chamber in the end of the thimble is filled with sand and leveled off after the eye has been placed in the chamber and previous to the placing of the thimble in position. This is to prevent the metal from entering said chamber and from spoiling the eye of the weight. After the weights have been cast and removed from the sand the thimbles drop off from the eye of the weight, and are used for casting more weights.

In the drawings, Figure 1 represents a plan view of the mold-board with the gate and weight patterns and the lower half of the flask in position ready to be filled with sand. Fig. 2 represents a longitudinal section of the same on the line A B in Fig. 1, showing the lower half of the flask filled with sand and leveled off. Fig. 3 represents a cross-section of the same on the line C D in Fig. 1, showing the flask filled with sand, leveled off, and having the bottom board of the flask placed in position on the flask. Fig. 4 represents a plan view of the mold after the lower half of the flask with the gate and weight patterns, mold-board, sand, and bottom board have been turned right side up, the mold-board removed, the sprue, shutting-off and cutting-off patterns, and the upper half of the flask placed in position ready to have the flask filled with sand. Fig. 5 represents a longitudinal section of the same on the line E F in Fig. 4, showing the flask filled with sand and leveled off. Fig. 6 represents a cross-section of the same on the line G H in Fig. 4, also showing the flask filled with sand and leveled off. Fig. 7 represents a plan view of my improved mold ready to cast the weights. Fig. 8 represents a longitudinal section of the same on the line I J in Fig. 7. Fig. 9 represents a cross-section of the same on the line K L in Fig. 7. Figs. 10 and 11 represent detail views of the strap of wrought-iron or steel used in making the eye of the weight before and after it has been bent to the required form. Figs. 12 and 13 represent detail views of the thimble for holding the eye of the weight while it is in the mold. Figs. 14 and 15 represent detail view of the thimble and the eye ready to be placed in the mold, and Figs. 16 and 17 represent detail views of the sash-weight.

Similar letters refer to similar parts wherever they occur on the different parts of the drawings.

In Figs. 16 and 17, *a* represents a sash-weight, the lower end *a'* of which is made tapering, as shown, to enable the weights to more readily pass each other while the sashes are being operated, and not to get caught, as is sometimes the case with the ordinary weights, which are molded in a vertical position, and therefore are of the same size throughout their entire length. The eye of the weight is made from a strap *a''* of wrought-iron or steel, (shown in detail in Figs. 10 and 11), said strap being provided with a per-

foration *a³*, through which the sash-cord passes in hanging the weight, and also with one or more notches, perforations, or irregularities *a⁴ a⁴*, at or near the ends of the strap *a''*, to prevent it from being drawn out of the weight after it has been bent to the required form and cast in the weight, as shown in Figs. 16 and 17.

I stamp the strap *a''*, from which the eye of the weight is made, with a figure or with letters denoting the size of the weight. This may be done before or after the eye has been cast in the weight; but I prefer to stamp said strap before attaching it to the weight.

The molds for casting the weights are made as follows: *b* represents a mold-board having grooves *b' b'*, in which are placed the weight-patterns *c c c*. Said patterns are made longer than the largest weight that is to be cast from these patterns, and are placed on the mold-board *b* in one or two rows, according to the size of the flask. The tapering ends *c' c' c'* of the weight-patterns *c c c* abut against the edges of the gate-pattern *d*, which is laid on the mold-board between suitable guides *d' d' d' d'* on said mold-board, which hold it in place. After the gate-pattern *d* and weight-patterns *c c c* have been placed in their proper places on the mold-board *b* the lower half *e* of a two-part flask is placed upside down on the mold-board and the flask filled and rammed up with sand. The patterns *c c* and *d* are made long enough to project through grooves on the edges of the side and ends of the flask *e*, and to allow them to be easily grasped by the hand of the molder. The bottom board *f* of the flask is then placed on top of the lower half *e* of the flask and the whole turned right side up and the mold-board *b* removed from the top, leaving the weight-patterns *c c c* and gate-pattern *d* embedded in the sand. The upper half *e'* of the flask is then put in position on top of the lower half *e* and a sprue-pattern *g* placed edgewise on the gate-pattern *d*, in or near the center of the same, also a shutting-off pattern *h*, placed edgewise on the gate-pattern *d*, against the side of the flask *e'* where the gate-pattern projects through the flask, all as shown in Figs. 4, 5, and 6. I then place the cutting-off patterns *i i* over the ends of the weight-patterns *c c c*—one at each end of the flask *e'*—in such a position that their inner edges will come on a line with one of the several marks *c'' c''* on the weight-patterns *c c*, the particular mark being determined by the size of the weight that is to be cast. I also fill the spaces between the cutting-off patterns *i i* and the ends of the flask with one or more pieces *i' i'*, to prevent the sand from moving the patterns *i i* when the flask is being rammed up.

k k represent the top boards of the flask, which are placed on the flask after it has been filled with sand and leveled off, and *l l* represent suitable clamps, which clamp the parts *e e'* of the flask, with their top boards *k k* and bottom board *f*, together. I do not wish to

confine myself to the use of the clamps shown in the drawings, as other and well-known clamps or a weight may be used, if so desired, without departing from the spirit of 5 my invention.

After the flask has been clamped together, I remove the gate-pattern *d* by drawing it through the perforation *e''* in the side of the flask. (Shown in Fig. 9.) I also remove the 10 sprue-pattern *g* and shutting-off pattern *h* and throw a little sand in the hole made in the sand by the removal of the latter, and as said hole communicates with the outer end of the gate *d''*, made in the sand by removing the 15 gate-pattern *d*, it will be seen that I shut off the gate *d''* and prevent the metal from escaping from the gate at this point. I proceed by drawing out the weight-patterns *c c c* through the perforations *e³ e³* in the ends of the 20 flask (shown in Fig. 8) and by drawing the cutting-off patterns *i i* from the top of the flask, the pieces *i' i'* remaining in the flask, or not, according to whether they are needed to make another mold or not. It will be seen 25 by removing the cutting-off patterns *i i* that a free access is made to the ends of the spaces *c³ c³* made in the sand by the weight-patterns *c c*. This enables the thimbles *m m* to be inserted in the ends of the spaces *c³ c³*, and also 30 allows space for sand to be placed back of the thimbles *m m*, to prevent the metal from forcing the thimbles out and allowing the metal to escape from the ends of the spaces *c³ c³*.

Before the thimbles *m m* are put into the 35 spaces *c³ c³* one of the bent eyes *a'' a³ a⁴* is placed in the chamber *m'* in each of the thimbles and the chamber filled with sand, as shown in Fig. 15. The ends of the strap *a''*, which forms the eye of the weight *a*, projects 40 beyond the end of the thimble *m* into the space *c³*, when the thimble is placed in said space, so as to allow the metal to surround said ends and embed them in the body of the weight *a*. The ends of the strap *a''* are made 45 irregular or with notches *a⁴ a⁴*, so as to prevent the strap from being drawn out of the weight after it has been cast in it. The sand placed in the chamber *m'* in the thimble *m* prevents the metal from entering said chamber and from spoiling the eye of the weight. 50

It will be seen that as the tapering ends *c' c'* of the weight-patterns *c c* rest against the edge of the gate-pattern *d*, a passage is made 55 into the spaces *c³ c³* from the gate *d''* for the metal poured into the sprue and through the gate *d''*, and as such passage is considerably smaller than the diameter of the weight, the metal remaining in the gate after the mold has been poured and cooled off can easily be 60 separated from the weights by a light blow without injury to the weights.

In casting weights in this my improved

mold less skilled molders are required, and the weights are cast seamless, as the mold is not disturbed until the weights are cast and 65 partially cooled off, whereas in the ordinary molds for casting weights a skilled molder is needed, as the mold has to be lifted apart to remove the patterns, and if the sand is not tempered and rammed up properly the mold 70 will fall apart. It is also very difficult to replace the upper half of the flask in exactly the same place on the lower half, and if it is not in the same position the weights are cast with a bad seam and are irregular in form. 75

In the ordinary way of casting weights separate patterns are required for the different sizes of weights, whereas by my improved method only one pattern is needed to cast all sizes of weights that are of the same diameter, 80 it only being necessary to move the cutting-off pattern nearer to or farther away from the end of the weight-patterns.

If so desired, I may dispense with the cutting-off patterns *i i* and introduce the thimbles *m m* into the spaces *c³ c³* through the perforations *e³ e³* in the ends of the flask, and then fill the spaces behind them with sand; but I prefer to use the cutting-off patterns, 85 as they are more handy and the weights can be 90 made more of a uniform size.

Having thus fully described the nature, construction, and operation of my invention, what I wish to secure by Letters Patent, and claim, is—

95

1. In a mold for casting sash-weights, the weight-patterns *c c c*, with the cutting-off patterns *i i* and thimbles *m m*, in combination with the gate-pattern *d*, with the shutting-off pattern *h* and sprue-pattern *g*, all arranged 100 as described, for the purpose set forth.

2. In a mold for casting sash-weights, the weight-patterns *c c c*, in combination with the cutting-off patterns *i i* and thimbles *m m*, having chambers *m' m'*, for holding the eye 105 of the weight while it is being cast, as and for the purpose set forth.

3. In a mold for casting sash-weights, the gate-pattern *d*, in combination with the sprue-pattern *g* and shutting-off pattern *h*, as and 110 for the purpose set forth.

4. In a mold for casting sash-weights, gate-pattern *d*, with the sprue-pattern *g* and shutting-off pattern *h*, in combination with the weight-patterns *c c c* and thimbles *m m*, provided with the chambers *m' m'*, for the purpose set forth and described. 115

In testimony whereof I have affixed my signature in presence of two witnesses.

ADDISON S. HODGES.
